US00D858805S

(12) **United States Design Patent** (10) **Patent No.:** **US D858,805 S**
Meyers (45) **Date of Patent:** **** Sep. 3, 2019**

(54) **SIDEWALK TILE**(71) Applicant: **TUF-TITE, INC.**, Lake Zurich, IL (US)(72) Inventor: **Theodore W. Meyers**, Barrington, IL (US)(73) Assignee: **TUF-TITE, INC.**, Lake Zurich, IL (US)(**) Term: **15 Years**(21) Appl. No.: **29/590,920**(22) Filed: **Jan. 13, 2017****Related U.S. Application Data**

(60) Division of application No. 29/545,032, filed on Nov. 9, 2015, now Pat. No. Des. 780,346, which is a division of application No. 29/479,189, filed on Jan. 13, 2014, now Pat. No. Des. 744,668, which is a division of application No. 29/459,722, filed on Jul. 2, 2013, now Pat. No. Des. 700,369, which is a division of application No. 29/439,118, filed on Dec. 6, 2012, now Pat. No. Des. 691,743, which is a continuation of application No. 13/349,309, filed on Jan. 12, 2012, now Pat. No. 8,920,066.

Primary Examiner — Kevin K Rudzinski*Assistant Examiner* — Kimberly Barnes*(74) Attorney, Agent, or Firm* — Marshall, Gerstein & Borun LLP(57) **CLAIM**

The ornamental design for a sidewalk tile, as shown and described.

DESCRIPTION

FIG. 1 is a top plan view of a sidewalk tile showing my new design; and,

FIG. 2 is a side elevation view of the sidewalk tile of FIG. 1.

The portions of the article shown in dashed lines in the FIGURES illustrate features that form no part of the claimed design. The dash-dot-dash lines illustrate boundaries and form no part of the claimed design.
